V TYPE BEDPLATE FOR PAPER PULP BEATERS

Archer Le Roy Bolton, North Andover, Mass., assignor to John W. Bolton & Sons, Inc., Lawrence, Mass., a corporation of Massachusetts

Application July 8, 1936, Serial No. 89,540

3 Claims. (Cl. 92—22)

This invention relates to beater engines used in preparing the stock for paper making and particularly to the bedplates used in such engines.

5 The usual beater engine includes an oval tank in which a cylindrical beater roll revolves so as to carry the stock up and over a backfall and against knives in what is known as a bedplate.

The beater roll is provided with radially projecting bars of metal and the bedplate is usually made up of knives made of metal, the faces of the knives and bars coming close together.

10 The knives and bars, therefore, wear out and should be and generally are replaceable. The 15 bedplate is located in a box usually of metal which is a relatively permanent part of the machine and is located either directly under the axis of the roll, in the backfall, or sometimes in other locations. This invention has to do with 20 the type of bedplates which are made up of a plurality of metal knives bolted or otherwise fastened together as a unit which can be installed in or removed from a holding box. Such assembled bedplates are usually installed in the 25 bedplate box and are held in place by wooden fillers or cheek pieces and by wedges.

20 In some cases, all the knives are of the same thickness while in others, the front and back knives, which I will call holding knives, are relatively thick and heavy, while the knives between them are relatively thin and are frequently separated by fillers of wood or other material. In 30 some cases, the thin intermediate knives are corrugated or curved in S shapes when viewed from the top.

35 I am aware there are bedplates in which the knives are straight and run parallel with the front and back of the box and with the axis of the beater roll, and I am also aware that there 40 are bedplates known as elbow bedplates in which the knives are bent slightly in the middle, each branch forming an angle of from 2 to 6 degrees with the front or back of the box and with the axis of the roll.

45 I am also aware that there are bedplates in which the knives form a much greater angle, such as from 35 to 45 degrees, with the back and front of the box and the axis of the roll, all knives sloping in the same direction.

50 When the angular or elbow bedplate is put in a box, the single triangular space at the back and the two triangular spaces at the front are filled with cheek pieces generally of wood, which simply fill the spaces and with the wedges help 55 to hold the bedplate in position,

For convenience, I will call the base, any line parallel with the axis of the beater roll and with the front and back of the holding box.

This invention is the use of knives which diverge from the middle of the back at a high 5 angle, preferably between 35 and 45 degrees in both directions toward the front, meaning by front the place where the stock enters as it is carried along by the beater roll.

In other words, the knives converge from the 10 front towards the middle of the back and make with the base a large instead of a small angle.

One purpose of this device is to correct the tendency of the stock to work out at each side, which 15 tendency necessitates certain precautions in making the roll and other parts, and to direct the heavier, coarser stock toward the middle of the roll and of the bedplate instead of being allowed to escape at the sides.

The part of the stock which is in best condition 20 will, therefore, pass through on the sides and the stock which needs more treatment will automatically be directed toward the center where it comes into the relatively sharp angle between the middle knives from which it is very 25 difficult to escape the action of the beater roll bars or blades.

My construction can be used with a bedplate having relatively heavy straight front and back holding knives or with the elbow construction 30 having bent front and back holding knives, and with the intermediate knives either of the same thickness as the holding knives or of a different thickness. In any event, the intermediate knives 35 diverge at a fairly large angle, such as from sixty to one hundred and twenty degrees, while the front and back knives may be parallel or may be bent so that their end portions diverge at a much greater angle, such as one hundred and 40 sixty to one hundred and eighty degrees.

In every case, the cutting knives or members converge from the front to the middle of the back, their end portions making an angle of between thirty and sixty degrees with the base 45 while the angles of the ends of the holding knives, if there are any, with the base are much less, as from nothing to perhaps twenty degrees.

In a modification, I can use the angle or elbow type with front and back angular holding knives 50 and also additional straight parallel holding knives between which are still other intermediate knives which may be set at a still different angle.

In the drawings,

Fig. 1 is a diagrammatic plan view of a beater engine.

Fig. 2 is a sectional side elevation showing the beater roll, backfall and bedplate of a typical beater engine.

Fig. 3 is a plan view of a beater engine bedplate receiving box removed from the beater and with a preferred form of bedplate in place.

Fig. 4 is an elevation as from the left of Fig. 3.

10 Fig. 5 is a plan view similar to Fig. 3 of a modified construction, and

Fig. 6 is an elevation from the left of Fig. 5.

Fig. 7 is a plan view similar to Figs. 3 and 5 of another modification, and

15 Fig. 8 is an end view from the left of Fig. 7.

Fig. 9 is a plan view similar to Fig. 3 of another modification, and

Fig. 10 is an elevation as from the left of Fig. 9.

Fig. 11 is a plan view similar to Fig. 3 of another modification, and

20 Fig. 12 is an elevation as from the left of Fig. 11.

Fig. 13 is a plan view similar to Fig. 3 of another modification, and

25 Fig. 14 is an elevation as from the left of Fig. 13.

Fig. 15 is a plan view similar to Fig. 3 of another modification, and

Fig. 16 is an elevation as from the left end of 30 Fig. 15.

Fig. 17 shows another means of holding the cutting members together, and

Fig. 8A is a detail of a preferred form of bolt.

In the drawings, A represents the oval tub common in beater engines, 90 is the midfeather and 91 is the backfall. B is the receiving box for the bedplate P and C is a beater roll of the ordinary type, while W represents the wedge generally used to hold the bedplate in the receiving 40 box.

In Figs. 3 and 4, P represents a bedplate of what is known as the elbow type in which 1 is a relatively thick and strong bent back holding knife and 2 is a relatively thick and strong front holding knife. The ends 7, 7 of back knife 1 are preferably somewhat bent so as to reduce the number of short intermediate end cutting knives 5, 5 between which are relatively short separating members 6, 6 while 3, 3 represent the longer 45 intermediate cutting knives which, as shown, are thinner than the holding knives 1 and 2 and which radiate in opposite directions from the middle of the back holding knife 1, like fishbones. These intermediate knives 3 are separated by separating 50 members 4, 4 which, as shown, are of less height than the knives and which may be of wood or other suitable material.

This assembled bedplate P is held together as a unit by bolts such as 80 which pass through 55 suitable holes in the front and back holding knives 1 and 2 and through the intermediate knives 3 and 5 and separators 4 and 6.

Preferably the cutting knives 8 at the middle are bent in the form of a V and these determine the angle of the other cutting knives 5, 5 and 3, 3, and also the angle of the ends 7, 7 although it is obvious that these center knives 8, 8 might each be made of two smaller knives brought together at one end.

70 Box B has a back 101, front 102 and one end 103.

Between the back 101 of the box B and the back of holding knife 1 is a cheek piece 93 in the form of a double wedge with the small parts 75 combined, and between the front wall 102 and

the front holding knife 2 is another cheek piece 92 of triangular shape which is, however, separated from the front wall 102 by a wedge W which is driven in from one end so as to hold the entire assembly together and permit the receiving box B, the bedplate proper P, together with the cheek pieces 93 and 92 to be handled as a unit. The intermediate knives 3 and 5 radiate from the middle of the back at angles of approximately 38° in both directions towards the front 10 or converge from the front towards the middle of the back.

In Figs. 5 and 6, the bodily transportable unitary bedplate M is made up of the front and back relatively thick holding knives 12 and 11 15 substantially of the same shape as 2 and 1, but in addition, there are the front straight relatively thick holding knife 19 and the back relatively thick holding knife 18 with bent ends 17, 17, there being a cheek piece 95 similar to 92, between holding knives 12 and 19, and another cheek piece 96, similar to 93, between the bent and straight holding knives 11 and 18, the whole assembly being held together by bolts such as 81 and 181. This is installed as a unit in a box B and is held 25 in place as a unit by a wedge W.

As shown in Figs. 7 and 8, I may use a bodily transportable unitary bedplate N made up of front and back bent holding knives 21 and 22 between which are the intermediate cutting knives 30 23 and 25 separated by separators 24 and 26, together with a relatively thick strong straight front holding knife 29 and a similar straight back holding knife 28, preferably with bent ends 27, 27.

Between the front bent holding knife 22 and 35 straight front holding knife 29 are additional cutting knives 73 between which are separators 72 and between the back bent holding knife 21 and the back straight holding knife 28 are other additional cutting knives 71 between which are 40 separators 70, the knives 71 and 73 being substantially parallel with the adjoining arms of the bent separators 21 and 22. Bolts 82 and 182 hold the assembly together.

In Figs. 9 and 10, the construction is similar 45 to that shown in Figs. 7 and 8. The unitary assembled bedplate O is made up of front and back bent holding knives 31 and 32 between which are intermediate cutting knives 33 and 35 and separators 34 and 36, while between the front 50 bent holding knife 32 and the front straight holding knife 29 are the converging cutting knives 77 between which are separators 76 and between the bent back holding knife 31 and the straight back holding knife 38 with bent ends 78, 78, are 55 other relatively short converging or diverging cutting knives 75 between which are separators 74. This assembled unit is held together by bolts 83, 183 and rivets 178.

Where, as in Figs. 7 and 9 at 27 and 78, there are 60 short knives and separators extending out, I prefer to rivet them to one of the holding knives as by a rivet 85.

In Fig. 3, the head and nut of bolts 80 are countersunk in the cheek pieces, but bolts 81, 181, 65 82, 83, 182 and 183 are made with the conical heads and nuts shown in Fig. 8A, and are countersunk in the holding knives. The nuts are cut off at the dotted line as shown.

In Figs. 11 and 12 is shown an assembled bodily 70 transportable unitary bedplate R in which there are no bent holding knives but there are the front straight holding knife 49 and the back straight holding knife 48 with bent ends 47, 47 and between these, converging from the front 75

toward the middle of the back are the relatively long cutting knives 43 between which are separators 44 and relatively short cutting knives 45 between which are the relatively short separators 46. This assembly is held together by rivets 84 and 87.

As shown in Figs. 13 and 14, instead of assembling a plurality of parts as in the bedplates hereinbefore described, I can use a cast metal unit bedplate such as S in which the front is 52 and back 51, the relatively long cutting knives are represented by 53 and the spaces between by 54, while 55 represents the short cutting knives and 56 the separating spaces between them. In this construction no holding knives and no bolts are required.

As shown in Figs. 15 and 16, a bedplate T can be assembled with no separating members, each cutting knife 63 or 65 having its cutting edge bevelled off as shown so that the knives 63 and 65 serve as their own separating members, leaving triangular channels 64 or 66 between them.

These may be assembled as in the elbow bedplate of angular construction, or of the straight construction such as shown in Figs. 11 and 12, the front holding knife 62 and the back holding knife 61 being shown as of less height than the other knives. 61 is bent at each end 67. This assembly is held together by rivets 86 and 88.

Such knives 63 can be assembled and spot welded together as at 68 instead of being bolted or riveted.

I claim:

1. The combination in a beater engine having a beater roll carrying radially disposed bars and a bedplate box; of a bodily transportable bedplate in the box having at the front and back straight holding knives parallel with the axis of the roll; bent holding knives between the straight knives which are so bent that their ends con-

verge from the front towards the center of the back at a relatively small angle with the base; intermediate knives between the front and back bent holding knives which converge from the front toward the center of the back at a relatively great angle with the base; separating members of less height and between the intermediate knives; other intermediate knives in the angular spaces between the bent and the straight holding knives; and separating members between these last named intermediate knives; together with means to hold the bedplate assembly together as a bodily transportable unit. 5 10

2. The combination in a beater engine having a beater roll carrying radially disposed bars and a bedplate box; of a bodily transportable bedplate in the box having at the front and back straight holding knives parallel with the axis of the roll; bent holding knives between the straight knives which are so bent that their ends converge from the front towards the center of the back at a relatively small angle with the base; intermediate knives between the front and back bent holding knives which converge from the front toward the center of the back at a relatively great angle with the base; separating members of less height and between the intermediate knives, together with means to hold the bedplate assembly together as a bodily transportable unit. 15 20 25

3. A bodily transportable bedplate made up of angular holding knives which are so bent that their ends converge from the front towards the center of the back at a relatively small angle with the base; intermediate knives between the front and back bent holding knives which converge from the front toward the center of the back at a relatively great angle with the base; together with means to hold the bedplate assembly together as a bodily transportable unit. 30 35

ARCHER LE ROY BOLTON. 40
